UNITED STATES PATENT OFFICE.

WILLIAM HOLLOWAY, JR., OF WAYNE, PENNSYLVANIA.

ELECTRIC RAILWAY-SIGNAL.

SPECIFICATION forming part of Letters Patent No. 470,129, dated March 1, 1892.

Application filed August 21, 1891. Serial No. 403,294. (No model.)

To all whom it may concern:

Be it known that I, WILLIAM HOLLOWAY, Jr., a citizen of the United States, residing at Wayne, in the county of Delaware and State 5 of Pennsylvania, have invented certain new and useful Improvements in Electric Railway-Signals, of which the following is a specification.

My invention has relation to electric rail-
way-signals, and has for its object the pro-
vision of novel, simple, and efficient means
whereby the opening of a switch will operate
to close an electric circuit, in which latter is
an alarm on the engine of an approaching
train when the same has reached a predeter-
mined position on the track in which the
switch is located, thus notifying the engineer
of the condition of the switch in time to avoid
disaster.

My invention consists in the apparatus
hereinafter fully described and claimed, and
as shown clearly in the accompanying draw-
ings, wherein—

Figure 1 is a plan view of a portion of a
railway provided with the circuits and their
appurtenances necessary for the operation of
my invention. Figs. 2 and 3 are respectively
a front and side elevation of a locomotive
adapted for use on the railway illustrated in
Fig. 1, and Fig. 4 is a detail view of the cir-
cuit-closer operated by the switch-rod.

In said drawings, A A' represent the rail-
way-rails, secured in the usual manner to the
cross-ties *a* and having the switch-rails B B'.
C is the switch-rod, and *c* the switch-lever,
for the movement of the rails last mentioned.

D D' represent supplemental rail-sections
intermediate the main rails A A' and at such
distance from the switch as to avoid impossi-
bility of the stopping of a locomotive under
ordinary circumstances at a point interme-
diate said supplemental rails and the open
switch.

E is the electric battery, and *e e'* the main
wires leading therefrom, the wire *e* being con-
nected at its outer end to the rail-section D'
and the wire *e'* being connected to the con-
tact-point *f*² of the electric switch F. The
wire last mentioned has a branch *e'* connected
to the terminal *g*, and the terminal *g'* has
connected thereto a wire G, which at its outer
end is connected to the rail-section D, this

latter section having also connected thereto
a wire *f*, which wire is connected to the post
of the electric switch-lever *f'*. The terminals 55
g g', while being represented as in contact,
are of course normally separated and may be
so maintained in the manner shown in Fig. 4
of the drawings or otherwise.

The locomotive H is provided with brushes 60
h h', secured in the insulating-tubes *h*² *h*³,
and have connected thereto the wires *k k'*,
which latter are secured at their other ends
to the bell or alarm K in the cab of the engine.
Obviously when the engine H has reached 65
such a position on the track as to bring the
brushes into contact with the rail-sections D
D', (the terminals *g g'* having been placed in
contact through the impact of the free end of
the switch-rod C when the switch is opened,) 70
the circuit composed of the wire *e*, the rail-
sections D D', the wire G, the terminals *g g'*,
the branch *e'*, and the lower portion of the
wire *e'* will be closed by the interposition of
said brushes, their wires *k k'* and the bell K 75
causing the sounding of the latter and result-
ing in the giving of the desired notice to the
engineer of the open condition of the switch.
When the switch is closed, the terminals *g g'*
will of course be out of contact and the bell 80
remain silent, from which fact the engineer
knows that he can go ahead safely. If, how-
ever, it be found desirable from any cause to
stop the locomotive before the same reaches
the switch and irrespective of the condition 85
of the same, such an end can be accomplished
manually through the medium of the electric
switch F, which latter may be located in a
watch-box or elsewhere. The lever *f'* being
turned so as to bring its outer end into con- 90
tact with the contact-point *f*² of said switch
results in the formation of a circuit through
the battery-wire *e*, the rail-section D', the
brush *h*', the wire *k*', the bell K, the wire *k*,
the brush *h*, the rail-section D, the wire *f*, the 95
switch F, and the wire *e'*, thus attaining the
desired end.

In Fig. 4, hereinbefore mentioned, the ter-
minals *g g'* are shown as being secured to an
insulating spring-controlled disk *l* and are 100
bent away from the plane of the face thereof
and are out of contact with each other. This
disk is sustained on a plunger *l'*, which slides
in a suitable opening in the cylinder L, said

plunger being encircled by the spring β , which spring occupies a position intermediate the outer end of the cylinder and the inner side of the disk. With this device if the switch-rod C be a little long the disk will yield when the terminals have been brought into contact and allow the switch to be fully opened. Thus the support for the terminals accommodates itself to variations in the length of the switch-rod without necessitating the accurate adjustment of the positions of the terminals relatively thereto, at the same time insuring a close contact of said terminals.

What I claim as my invention is as follows:

1. In a railway-signal, the combination of a pair of supplemental rail-sections intermediate the main rails, a battery, circuit connections between said battery and sections, an alarm on the locomotive, brushes on the latter connected with the alarm and for contact with the rail-sections, the terminals $g g'$, sustained on the disk l , the spring β , encircling the plunger l' of said disk, the cylinder L , receiving said plunger, and the switch-rod C, the latter at its free end bearing against

and operating by its impact to bring said terminals together when the switch is open, substantially as and for the purpose specified.

2. In a railway-signal, the combination of the rail-sections D D', a battery, the terminals $g g'$, sustained on the disk l , the spring β , encircling the plunger l' of said disk, the switch-rod C, the wires e and G, the branch wire e^2 , the wire e' , the brushes $h h'$, the alarm K, and the wires $k k'$, substantially as and for the purpose specified.

3. In a railway-signal, the combination of the rail-sections D D', a battery, the terminals $g g'$, sustained on the disk l , the spring β , encircling the plunger l' of said disk, the switch-rod C, the wires e and G, the branch wire e^2 , the wire e' , the brushes $h h'$, the electric switch F, the wire f, the alarm K, and the wires $k k'$, substantially as and for the purpose specified.

In testimony whereof I have hereunto set my hand this 18th day of August, A. D. 1891.

WILLIAM HOLLOWAY, Jr.
